(57) **CLAIM**

The ornamental design for in-store self-checkout machine, as shown and described.

DESCRIPTION

FIG. 1 is a perspective view of an in-store self-checkout machine showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is an enlarged perspective view thereof with the PIN input keys and receipt dispensing slot shown separately for purposes of illustration;

FIG. 9 is an enlarged perspective view thereof with the coin input tray and coin dispensing tray shown separately for purposes of illustration; and,

FIG. 10 is an enlarged perspective view thereof with the paper currency slot and paper currency dispensing slot shown separately for purposes of illustration.
